[57] CLAIM

The ornamental design for a motorcycle tire, as shown
and described.

DESCRIPTION

FIG. 1 is a front perspective view of a motorcycle tire
showing my new design, it being understood that the
tread design is repeated uniformly throughout the cir-
cumference of the tire and the opposite side is the same
as that shown.

FIG. 2 is a front elevational view thereof;

FIG. 3 is a top plan view thereof;

FIG. 4 is a rear elevational view thereof;

FIG. 5 is a right side elevational view thereof; and,

FIG. 6 is an enlarged front elevational view of the
groove portions thereof.

FIG. 1

FIG. 2

FIG. 3

FIG. 4

FIG. 5

FIG. 6
